UNITED STATES PATENT OFFICE.

JANET BURD ROWLAND, OF YONKERS, NEW YORK.

DESIGN FOR A RAG DOLL.

49,675.

Specification for Design. **Patented Sept. 19, 1916.**

Application filed March 16, 1916. Serial No. 84,731. Term of patent 14 years.

To all whom it may concern:

Be it known that I, JANET BURD ROWLAND, a citizen of the United States, and a resident of Yonkers, in the county of Westchester and State of New York, have invented a new, original, and ornamental Design for a Rag Doll, of which the following is a specification, reference being had to the accompanying drawings, forming a part thereof.

Figure 1 is a front perspective; Fig. 2 is a side elevation; and Fig. 3 is a rear elevation of a rag doll showing my new design.

I claim:—

The ornamental design for a rag doll, as shown.

JANET BURD ROWLAND.
